UNITED STATES PATENT OFFICE

103,949

DESIGN FOR A DISPLAY CABINET

John F. Meyer, Chicago, Ill.

Application January 18, 1937, Serial No. 67,125

Term of patent 3½ years

To all whom it may concern:

Be it known that I, John F. Meyer, a citizen of the United States, and a resident of Chicago, in the county of Cook and State of Illinois, have invented a new, original, and ornamental Design for a Display Cabinet, of which the following is a specification, reference being had to the accompanying drawing, forming a part thereof, and in which:

The figure is a perspective view of a display cabinet showing my new design.

I claim:

The ornamental design for a display cabinet, as shown.

JOHN F. MEYER.
